UNITED STATES PATENT OFFICE.

EDGAR B. WILLS, OF MENDOTA, ILLINOIS.

SUBMERGED-TANK HEATER.

No. 908,182.

Specification of Letters Patent.

Patented Dec. 29, 1908.

Application filed May 19, 1908. Serial No. 433,733.

To all whom it may concern:

Be it known that I, EDGAR B. WILLS, a citizen of the United States, residing at Mendota, in the county of LaSalle and State 5 of Illinois, have invented certain new and useful Improvements in Submerged-Tank Heaters; and I do hereby declare the following to be a full, clear, and exact description of the invention, such as will enable others 10 skilled in the art to which it appertains to make and use the same, reference being had to the accompanying drawings, and to the letters and figures of reference marked thereon, which form a part of this specification.

15 This invention relates to new and useful improvements in submerged tank heating apparatus and the object in view is to produce an apparatus of this nature so arranged that either coal or wood may be equally well 20 used as fuel and having a fire box with a hinged end adapted to turn down, the apparatus being provided with a suitable slide utilized as a damper and also as a means for guiding fuel being inserted within the fire 25 box.

30 The invention comprises various details of construction, combinations and arrangements of parts which will be hereinafter fully described and then specifically defined in the appended claims.

I illustrate my invention in the accompanying drawings, in which:—

Figure 1 is a vertical sectional view through my improved submerged tank heater. Fig. 2 is a horizontal section on line 2—2 of Fig. 1. Fig. 3 is an enlarged detail of the fire box. Fig. 4 is a detail view of the slide serving as a damper and guide for the fuel, and Fig. 5 is a detail view of the 40 cover.

Reference now being had to the details of the drawings by letter, A designates a receptacle designed to be placed within a tank A² having an inlet pipe A³ in the top thereof, 45 and is adapted to contain in its lower portion a fire pan B and has a fire box C which is supported upon the ribs A' projecting from the opposite walls of the receptacle or casing. Said fire box, a detail of which is shown 50 clearly in the drawings, has an end C' provided with wings C⁴ mounted upon the pivots C² upon the side box and said end is designed when the apparatus is adjusted for use 55 for burning wood, to be turned down so that its inner surface will be flush with the upper surface of the bottom of the box, thus forming

ing an elongated receptacle or box. Projecting from the bottom of said box is a stop C⁵ which limits the inner throw of the ash pan positioned immediately below the fire 60 box. Said fire box has a grated bottom, as shown clearly in the drawings, and its forward end is inclined. A flue E extends from the end of the receptacle or casing in which the fire box is mounted and is made up preferably of sections connected together by water tight joints and said flue may extend in any suitable direction in order to increase the course through which the heat passes so that it may be distributed generally 65 through the water to be heated. In the drawings, the flues are shown as being provided with two elbows and having a damper E' positioned at any suitable location, preferably in the upright portion of the flue, 70 which is positioned adjacent to the rectangular outlined opening F of the casing.

Mounted within the grooves G arranged in pairs in the opposite walls of the upright portion of the casing is a slide H having lugs H' 80 at its lower end forming pivots upon which said slide tilts. The lower end of said slide is positioned adjacent to one end of the fire box and slides above the fire box and, when the slide is tilted down at an inclination as 85 shown in dotted lines in Fig. 1, it serves the purpose of a deflecting means for causing the fuel which is fed in the upper rectangular outlined portion F of the casing to be fed into the fire box. When thrown to an up- 90 right position, it is adapted to cut off the direct draft over the fire box and cause the draft to pass underneath the fire box, thence through the flue.

A suitable cover I is placed over the top of 95 the receptacle casing and provided with a draft door J having a handle J', said door being held by means of the cleats K and arranged to slide back and forth to regulate the amount of air being fed through the 100 apparatus.

It will be noted that the heater has ribs L upon the under side thereof in order to allow the latter to freely circulate underneath the same and for convenience in raising the fire 105 box a handle T is provided which may engage the staples T' formed upon the fire box. In order to hold the flue, the two plates R and R' are provided, each having recesses to receive the flue, one of said plates carrying 110 screws R² which engage slots R³ in the plate R, affording means for holding the plates

clamped in adjusted positions. In the drawings, I have shown one of said flue holding plates R' fastened to the flange of a heater and adjusted for holding the flue a distance 5 from the tank.

The operation of my invention will be readily understood when taken in connection with the drawings forming a part of this application. When coal or other similar material is utilized as fuel, the end of the fire 10 box is swung to its upright position and the slide tilted down at an inclination to guide the fuel to the box. When it is desired to utilize the box for burning wood, the end is thrown down to a horizontal position and fuel entered in the same manner as before. 15

By the provision of the adjustment of the slide, the draft may be directed above or beneath the fire box and the latter as well as the ash pan may be readily removed and replaced at will. When the parts are assembled, the apparatus may be placed within a 20 tank and the flue, which is made up of sections, may be run in any direction at any 25 length to carry the heat where desired.

What I claim to be new is:—

1. A submerged tank heater comprising a casing designed for insertion within a tank, a flue communicating with said casing, said 30 casing having upright walls with vertical grooves in the inner surface thereof, and horizontally disposed ribs, a fire box supported upon said ribs, a slide, pintles supported upon said ribs, a slide, pintles pro-

jecting therefrom and pivotally held in said grooves, said slide adapted to tilt at an angle 35 to guide fuel into the box, one end of the box being open, and an end hinged thereto and provided with wings and adapted, when swung outwardly, to provide extensions for the bottom and sides of the fire box, as 40 shown and described.

2. A submerged tank heater comprising a casing designed for insertion within a tank, a flue communicating with said casing, said casing having upright walls with vertical grooves 45 in the inner surface thereof, and horizontally disposed ribs, a fire box supported upon said ribs, a slide, pintles projecting therefrom and pivotally held in said grooves, said slide adapted to tilt at an angle to guide fuel into 50 the box, one end of the box being open, an end hinged thereto and provided with wings and adapted, when swung outwardly, to provide extensions for the bottom and sides of the fire box, a lug projecting from the bottom 55 of said box and serving as a stop, and an ash pan adapted to be inserted underneath said box and limited in its movement in one direction by said stop, as set forth.

In testimony whereof I hereunto affix my 60 signature in the presence of two witnesses.

EDGAR B. WILLS.
